UNITED STATES PATENT OFFICE

96,596

DESIGN FOR A SHOE

Samuel Epstein, New York, N. Y.

Application January 19, 1935, Serial No. 54,934

Term of patent 3½ years

To all whom it may concern:

Be it known that Samuel Epstein, a citizen of the United States, residing at New York, in the county of New York and State of New York, has invented a new, original, and ornamental Design for a Shoe, of which the following is a specification, reference being had to the accompanying drawing forming a part thereof.

In the accompanying drawing:—

Fig. 1 is a plan view of the shoe showing my new design.

Fig. 2 is a side perspective view of the shoe shown in Fig. 1.

The dominant features of my design reside in

a shoe having the entire surface covered by equidistant parallel lines of stitching with broad wavy lines also covering the entire surface of the shoe and running diagonally to the lines of stitching, said broad wavy lines being spaced at distances substantially twice the thickness of the lines and arranged parallel to each other, being inclined substantially forty-five (45°) degrees.

I claim:—

The ornamental design for a shoe, as shown and described.

SAMUEL EPSTEIN.
